DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

TUBE-CLEANING DEVICE.

Application filed June 20, 1922. Serial No. 569,703

My present invention will be best understood from the following description and the annexed drawings, in which Figure 1 is a section on line 1—1 of Fig. 2; Fig. 2 is a 5 side elevation of a portion of a heat-transfer device, such as a boiler, still or the like; Fig. 3 is an enlarged portion of Fig. 1; Fig. 4 is a more or less diagrammatic representation of a plan view of the tubes in Fig. 1; Fig. 5 is an enlarged plan view, partly broken away, 10 of the arrangement shown in Fig. 1; Fig. 6 is an enlarged view similar to Fig. 1, and Figs. 7 and 8 are side elevations of the bent tubes shown in the assembled views.

15 Like reference characters indicate like parts in the several views.

As an illustration of my invention, I have shown it in connection with a portion of an oil still in which there is an upper drum 10 20 and a lower drum 11 connected by tubes arranged in rows extending parallel to the axis of the boiler, these rows being numbered 12, 13, 14 and 15, respectively, in the drawings. In the form shown, the tubes are parallel to 25 each other throughout their length with their ends entered into upper and lower drums non-radially; in other words, the ends of the tubes are not bent at the point of entrance into the drums. In the form shown, the rows of 30 tubes are not staggered, but have the arrangement shown best in Figs. 4 and 5.

In all classes of structures used for heating fluids, it is necessary to clean the interior of the tubes from time to time, and this is 35 done usually by rotary tube cleaners of well-known types, all of which have some form of cleaner head which must be passed through the tube and which, therefore, must have some kind of a connection reaching to the outside, 40 both to control its movement through the tube and usually also to supply power to the cleaner. In some liquid-heating devices, it is necessary to clean the tubes quite frequently, and this is particularly true of oil stills in 45 which the carbon from the oil deposits on the interior of the tubes. In such structures, it is desirable to reduce the number of handholes as much as possible, always for the sake of economy and usually also in order to minimize the number of joints which must be kept 50 tight.

By my present invention I have provided a structure by which the number of openings

as well as the diameters of such openings may be made small and yet the tubes may be 55 cleaned readily.

In the form illustrated, the tubes are arranged in rows both longitudinally and cross-wise of the axis of the drum 10. The ends of the tubes 12, 13, 14 and 15 in each cross 60 row are symmetrically disposed on opposite sides of the vertical axial plane of the drum 10, so that tubes 12 and 15 are equidistant from and on opposite sides of such plane and similarly tubes 13 and 14 are equidistant from and on opposite sides of such plane. Handholes 10^a with their axes in the vertical axial 65 plane of drum 10 are provided in the side of the drum opposite the tube ends and are spaced along the drum so that a handhole is 70 midway between the vertical planes passing through a pair of adjacent cross rows of tubes. By this arrangement, each handhole 10^a, when viewed from above, is at the geometrical center of a group of tubes made up of two 75 tubes 12, two tubes 13, two tubes 14 and two tubes 15. It will also be obvious that, in the arrangement illustrated, the handhole 10^a is also opposite the geometrical center of a 80 group of four tubes, made up of two of the tubes 13 and two of the tubes 14, all of which are equidistant from such center. Likewise, it is obvious that the handhole 10^a is opposite the geometrical center of a group made up of 85 two of the tubes 12 and two of the tubes 15, all of which are equidistant from such center. Then, for the form of boiler or still illustrated, I provide two bent tubes 16 and 17 90 shown on a large scale in Figs. 7 and 8. The top of each of the tubes may be provided with a handle, as at 18, by which the tube may be more readily manipulated.

In use, the handhole fitting for the handhole opposite a group of tubes to be cleaned is opened, as shown in Fig. 1, and the tube 16 95 inserted through the handhole. The bend in the tube 16 is such that its lower end can be brought into contact with either one of the two tubes 12 of the group or either one of the two tubes 15 of the group. This is because 100 the handhole is located opposite the geometrical center of these four holes. With the tube 16 in the position shown in Fig. 1, the tube cleaner C will be entered into and guided by the bent tube 16 and will enter the 105 upper end of the tube 12, the hose H being

used to control the vertical motion of the cleaner C and also the power supply for the motor M of the cleaner C. The cleaner is preferably started up and made to rotate 5 while in the bent tube 16 so that it will effectively clean the uppermost end of the tube 12. The cleaner, by its rotation, removes the coating on the inner side of the tube in the usual manner, and the cleaner is lowered 10 through the extent of the tube. It is then withdrawn, preferably while in rotative motion, in order to further clean the tube 12, the rotative motion being preferably continued until the cleaner is within the tube 16. 15 The bent tube 16 is then rotated until its lower end is above the other of the tubes 12, which is cleaned in the same manner. Then, the bent tube 16 will be rotated until its lower end comes successively into contact with the 20 two tubes 15. The tube 16, in the form illustrated, is then withdrawn and the second bent tube 17 inserted, which is curved to bring its lower end into contact with two of the tubes 13 of the group and two of the tubes 14 of the 25 group in the same manner as just described for bent tube 16.

By providing a handhole for each group of tubes, as shown in Figs. 4 and 5, it is obvious that each of the tubes may be cleaned and yet 30 with the handholes not substantially larger in diameter and much less in number than the tubes themselves. In the form illustrated, there is only one handhole for each eight tubes.

35 It will be obvious that my invention may be applied to many forms of boilers, stills and the like, in which tubes are entered into drums, and that it may be used in connection with such arrangements when the ends of the tubes are bent so as to enter the drum radially.

It will also be obvious that the arrangement 40 would be applicable for cleaning a group of tubes entering a flat tube sheet.

45 It will also be understood that while I have shown my invention in connection with a fluid-heating arrangement having vertical tubes, it may be used with any other form, such as one having horizontal tubes.

50 I claim:—

1. A device for use with cleaning means for a plurality of tubes having their ends entered in the periphery of a drum at one side thereof and arranged in a group with 55 a plurality of tube ends in the group substantially equidistant from the geometrical center of the group, said drum having a hand-hole in the side of the drum opposite the tube ends and substantially opposite the 60 geometrical center of said group, said device comprising means to guide a cleaner from said handhole into the end of any one of the tubes in said group.

2. A device for use with cleaning means 65 for tubes having their ends entered in the

periphery of a drum at one side thereof and arranged in groups with a plurality of the tube ends in each group substantially equidistant from the geometrical center of the group, said drum having a handhole in the 70 side of the drum opposite the tube ends and substantially opposite the geometrical center of each of said groups, said device comprising means to guide a cleaner from one of said handholes into the end of any one of the 75 tubes in the group having its geometrical center opposite said handhole.

3. A device for use with cleaning means for tubes having their ends entered in the periphery of a drum at one side thereof 80 with said ends arranged in rows both parallel to and at right angles to the axis of said drum, said drum having a row of handholes in the side of the drum opposite the tube ends with their centers substantially opposite the 85 center of the space between a pair of rows of tube ends extending parallel to the drum axis and with the center of each handhole substantially opposite the center of the space between a pair of rows of tube ends extending at right 90 angles to the drum axis, there being one-half as many handholes as there are tube end rows at right angles to the drum axis, said device comprising means to guide a cleaner from one 95 of said handholes into any one of a plurality of tube ends.

4. A device for use with cleaning means for a tube having its end entered in the periphery of a drum, said drum having a hand-hole on the side opposite the tube end, with 100 the axis of the handhole out of alignment with the axis of the tube end, said device comprising means to guide a cleaner from said handhole into the end of said tube.

5. A device for use with cleaning means 105 for a tube having its end entered in the periphery of a drum, said drum having a hand-hole on the side opposite the tube end, with the axis of the handhole out of alignment with the axis of the tube end, said device 110 comprising a removable tube arranged to extend through the handhole to the tube and adapted to guide a cleaner from said hand-hole into the end of said tube.

6. A device for use with cleaning means 115 for a plurality of tubes having their ends entered in the periphery of a drum at one side thereof and arranged in a group with a plurality of tube ends in the group substantially equidistant from the geometrical center of the group, said drum having a hand-hole substantially opposite the geometrical center of said group, said device comprising 120 means to guide a rotary cleaner from said handhole into the end of any one of the tubes in said group with the cleaner rotating as it enters said end.

7. A device for use with cleaning means 125 for a tube having its end entered in the periphery of a drum, said drum having a hand- 130

hole on the side opposite the tube end, with the axis of the handhole out of alinement with the axis of the tube end, said device comprising means to guide a rotary cleaner from said handhole into the end of said tube with the cleaner rotating as it enters said end.

5 8. A device for use with cleaning means for a tube having its end entered in the periphery of a drum, said drum having a hand-

hole on the side opposite the tube end, with the axis of the handhole out of alinement with the axis of the tube end, said device comprising a removable tube arranged to extend through the handhole into contact with the end of the tube and adapted to guide a 15 cleaner from said handhole into the end of said tube.

DAVID S. JACOBUS.
